UNITED STATES PATENT OFFICE.

FRANCIS H. RICHARDS, OF HARTFORD, CONNECTICUT, ASSIGNOR TO THE KEMPSHALL MANUFACTURING COMPANY, A CORPORATION OF NEW JERSEY.

PLAYING-BALL.

SPECIFICATION forming part of Letters Patent No. 696,879, dated April 1, 1902.

Application filed March 5, 1902. Serial No. 96,728. (No model.)

To all whom it may concern:

Be it known that I, FRANCIS H. RICHARDS, a citizen of the United States, residing at Hartford, in the county of Hartford and State 5 of Connecticut, have invented certain new and useful Improvements in Playing-Balls, of which the following is a specification.

This invention relates to playing-balls such as used in playing base-ball and other games, 10 and is in the nature of an improvement upon the construction illustrated in my Patent No. 696,351, dated March 25, 1902.

Playing-ball cores or bodies have sometimes been made by winding tensioned rubber 15 thread into a ball. This does not, however, produce a solid ball, as the winding is irregular and numerous interstices occur, rendering the ball uncertain in action, so that it does not always give the same response to the same 20 blow. Moreover, the outer layer of elastic thread binds the inner layers, preventing them from acting longitudinally. Since the inner threads are merely placed under compression by the outer threads, the slight difference in 25 action obtained over that of a soft-rubber ball is scarcely enough to justify the expense of making a wound ball. Moreover, the rubber thread is not thoroughly cured and the effect of putting it under longitudinal tension is to 30 lessen its life, so that in a very short time the ball is rendered unfit for use. The action of even a low degree of heat is injurious to the tensioned and uncured rubber thread, causing 35 derangement of the shape of the ball, especially if the latter is allowed to lie with one side exposed to the hot sun, the cooler portions of the tensioned threads contracting as the other portions weaken in the heat.

The object of my invention is to avoid these 40 objections and to produce a ball which is capable of absorbing from a bat a great momentum, so that it may carry or fly a long distance. I aim to minimize the distortion of the ball, so as to avoid waste of driving force 45 in changing and restoring its shape. I also aim to produce a ball having uniform action, so that a given blow may always produce the same result, thus conduced to reliability and accuracy of action of the ball. I further aim 50 to prolong the life of the ball.

In the drawings forming part of this specification, Figure 1 is a cross-section of one kind of apparatus which may be employed in producing my improved core, a blank being shown in the apparatus and a stage of manufacture being also indicated. Fig. 2 is a view similar to Fig. 1, but showing a core as formed and ready to be withdrawn. Fig. 3 is a cross-section of a blank used in forming my improved ball, indicating one way in which said 60 blank may be made from sections. Fig. 4 is a view of a blank made in one piece. Fig. 5 is a view, upon a larger scale, of a ball made in accordance with my improvements, a portion being broken away, so as to exhibit the 65 interior.

In the several views similar parts are designated by similar letters of reference.

Preferably I employ a whole hollow sphere A, Fig. 4, made of soft india-rubber, which 70 may, if desired, be pure rubber, but is preferably a rubber compound having firmness and strength or toughness. An opening B communicates with the hollow C of the sphere, which may be made either integral, as at Fig. 75 4, or of hemispheres A' and A², Fig. 3, said hemispheres being suitably united.

I place the sphere A in a spherical chamber D, formed in a mold consisting of opposing halves E and F, having registering-dow- 80 els G and clamped together by any suitable means. Each of said members E and F may have one-half of the chamber D, which may be considerably larger than the blank sphere A. Into the opening B in the latter I insert 85 the mouth of a funnel H, which is shown as penetrating into the hollow C, although this is not important in all cases. By means of said funnel the interior C of the ball is placed in communication with a vessel or receptacle 90 J, formed or provided in the apparatus above the chamber D, said receptacle preferably being round and having a closely-fitting plunger K.

I place in the receptacle J a quantity of 95 material, preferably gutta-percha, which may by the action of heat be reduced to a plastic or fluid condition, as at L, Fig. 1. This material flows down the funnel H into the hollow of the rubber sphere A and drives out the 100

- air through a vent M, which in this instance is illustrated as a groove formed in the side wall of the main opening B and lying without the funnel H. In the portion F of the 5 mold there may be provided a vent N, communicating at P with the ball-vent M, so the air escaping from the ball may be conducted out of the apparatus. The fluid or plastic material may therefore settle or be forced by 10 the plunger K through the funnel H, so as to completely fill the interior of the ball A, whereupon the vent N in the mold may be closed by a screw-plug Q, Fig. 2, the overflow of the material into or through said vent 15 indicating to the workman that the hollow C has been filled. By means of suitable appliances the plunger K may be pressed still farther down, so as to force more of the filling material into the interior of the ball, causing 20 the walls thereof to yield and distending the ball until it completely fills the large spherical chamber D in the mold, as at Fig. 2. The air may escape from the chamber between the mold-section or through a vent T. 25 The gutta-percha or other material is allowed to pass from a liquid into a dry or hard condition while the plunger is still pressed down, so that the expanded condition of the rubber shell or envelop A³ is made permanent by 30 reason of this solidification of the core, (indicated by R, Figs. 2 and 5.) The core is thus closely joined to the envelop or mold in which it is molded. The mold may then be taken apart and the ball removed, the funnel 35 H being withdrawn and the hole left thereby in the ball being filled with a rubber plug S, Fig. 5. Preferably the diameter of the core R is more than half that of the complete ball. In practice I find that by making the core 40 two-thirds of the diameter of the finished ball excellent results are obtained when the core is made of gutta-percha compressed and the shell is of a firm quality of highly-vulcanized india-rubber.
- 45 At U is indicated a stitched cover, of leather, fabric, or the like, which prevents cutting of the rubber. This cover may be formed and placed upon the ball in the usual manner. The ball thus formed is well adapted for use 50 in base-ball and other games, and variations in the size, material, and proportions may be made in order to meet the requirements of different games. Preferably the leather cover is stretched or tensioned upon the body A³.
- 55 The principal effect of expanding a core within the envelop resides in producing a longitudinal tension of the latter, such tension, which of course extends in all directions around the ball, being indicated by concentric broken lines A⁴ at Figs. 2 and 5 and being most pronounced at or near the outer or surface portion of the ball. The inner portion of said envelop is also in a state of compression between the outer portion of the envelop and the core, such compression being indicated by radial lines A⁵ and being greatest near the inner surface of the envelop, where

said radial lines are thickest. Thus the inner portion of the envelop is practically in a state of compression, the median portion is both 70 compressed and tensioned, while the extreme outer portion is in a state of tension only. By the term "compression" I mean compressive tendency or action. It is not necessary that the core or its mold be condensed in bulk, 75 and if such condensation takes place it is due to the presence of air-spaces or impurities in the material.

It will be perceived that the material of the entire ball from center to periphery is in an 80 abnormal condition, the core being under compression and the envelop being both compressed and longitudinally tensioned, so that an extraordinary degree of efficiency is attained, every affected particle of the ball acting 85 with promptness and vigor in response to a blow. Although the outer part of the shell or jacket is in a soft condition and effectually cushions the blow of an implement, still the effect of a blow is different from the effect 90 upon a ball having a uniform softness of texture throughout. In the latter case a severe blow would violently distort the ball instead of giving the same impetus, whereas in my ball the softness resides only at the surface, 95 and as soon as this slight resistance is overcome a high resistance is met due to the presence of the relatively hard solid core, which not only itself absorbs momentum from the implement, but also by reason of its solidity 100 prevents undue distortion of the ball, so that nearly all of the force going from the implement to the ball is utilized to impart velocity thereto. It will also be understood that under the shock of a blow the solid core is slightly 105 displaced from its true central position, thereby affecting somewhat the material of the envelop at the opposite side of the ball from the implement and also affecting other portions of the envelop, so that almost, if not all of the 110 material of the envelop is called into action and instantly reacts, thereby imparting a high degree of activity or liveliness to the ball and causing the same to leave the implement at high velocity. Only a slight distortion is produced at any portion of the ball, whose entire 115 mass is thus rendered active in restoring the ball to its original spherical shape, and hence in reacting against the implement. It will be understood that the result of a blow will depend upon the velocity and weight of the implement as well as upon the weight of the ball, the depth of the depression produced in the ball, and especially upon the ratio of increase in resistance offered thereby. In this 120 instance this ratio is very high, the ball feeling quite soft to a light touch, but offering a hard resistance to pressure. The ball thus has practically all the desirable qualities of the usual soft-rubber ball and also a phenomenal flying or carrying power.

Owing to the rapidly-increasing resistance even a heavy blow effects only a slight distortion of the envelop and that only over a

small area thereof, so that very little force is absorbed in changing and rechanging the form of the ball. Moreover, the period during which the driver may continue to deliver power into the ball itself is increased, with the result of giving to the ball a longer flight. The compressed core not only retains the envelop in an expanded state, but also supports the same when struck, and by the combined elasticity of core and envelop an extremely active and powerful ball is produced.

It will be noted that my rubber envelop is different from one which is applied in the form of a green or uncured coating upon a center piece, since a coating made in such manner must be vulcanized in place, and in this process the whole mass of rubber becomes equalized in a density and inert or normally without tension. By having the interior of the rubber envelop or coating in a state of compression while the outer portion is in a state of longitudinal tension the efficiency of the ball is improved and the envelop is not merely an inert portion having no force or tension except that which is directly received from a driver.

It is to be understood that my invention is not limited in all cases to the use of a springy center piece or core, since other cores may be employed within the scope of the invention so long as a spherical or segmental elastic hollow ball or shell is permanently expanded over a solid or hard core which is too large for the original capacity of the former.

An important advantage of my invention resides in the durability of the finished ball, since instead of employing the partially-cured rubber threads of which the balls are wound, which are susceptible to many deleterious influences, I employ rubber of firm texture and highly vulcanized, and hence not liable to deterioration, so that the ball not only withstands severe usage, but remains in its original elastic condition for a long time. In the rubber-thread balls it is usual to stretch the thread nearly to the breaking-point while winding, and owing to such violent treatment the thread rapidly loses its life, particularly since it is not well cured, while in my ball better results are obtained by subjecting rubber which is well cured to considerably less tension, thereby conduced to long life of the ball. Moreover, by tensioning the rubber after the manner of my invention it is given a promptness in action which is not possible in a rubber-thread ball, the action of the inner layers whereof is seriously impeded by the binding effect of the outer layers of thread. Moreover, in a rubber-thread ball the tension

is in only one direction, whereas in my elastic envelop the tension is in all directions around the circumference of the ball, and hence the activity of all the particles of the rubber envelop is fully developed, or, in short, the ball carries no dead-weight. Moreover, the ball thus formed has a uniform solidity or density, which is not found in a thread ball on account of its interstices, and hence the same blow always produces the same result, enabling the user to play to better advantage.

Should the original ball A be somewhat imperfect or irregular in construction or form, the expansion and solidification of the core in the described manner is found to compensate for such imperfection or irregularity, since the rubber envelop is caused to fit smoothly to the walls of the spherical chamber D in the mold and such irregularities as may exist are caused to develop upon the inner surface of said envelop, where they become embedded with the solid core, and hence are rendered unobjectionable. Thus I produce a smooth true curvature of the periphery of the ball, which is a desideratum.

Modifications and variations may be resorted to within the scope of my invention.

Having described my invention, I claim—

1. A ball comprising a whole hollow rubber sphere in a state of expansion upon a solid core of gutta-percha, and a cover of leather or fabric upon said sphere.

2. A ball comprising an integral hollow rubber sphere in a state of expansion upon a solid core, and a leather cover upon said sphere.

3. A ball comprising an integral sphere of rubber expanded over a solid and relatively hard filling formed from plastic material and a stitched leather cover upon said sphere.

4. A ball consisting of a whole thick spherical india-rubber sphere, in a state of expansion over a solid sphere of gutta-percha and a leather cover stretched over said india-rubber sphere.

5. A ball comprising a whole sphere of firm india-rubber in a state of expansion over a solid sphere of gutta-percha, the diameter of the core being more than one-half that of said sphere, and a leather cover upon said sphere.

6. A ball consisting of a core formed of plastic material within a softer elastic sphere and holding the latter under tension, and a cover consisting of pliable fibrous material.

FRANCIS H. RICHARDS.
